CUTTING DEVICE FOR INSERTING ALBUM PICTURES

Clarence Klumb, Milwaukee, Wis.

Application September 18, 1937, Serial No. 164,600

4 Claims. (Cl. 30—294)

This invention relates to a cutting device for inserting album pictures.

The primary object of this invention is to provide a cutting device for the above mentioned purpose having a cutting blade adapted to engage an album leaf for the purpose of cutting a slot therein to receive the end edge of a photograph. In addition, the blade may be of such dimension as to be slightly wider than the thickness of a piece of album sheet paper.

A further object of this invention is to provide a cutter of the above mentioned character carried by a convenient hand block having a slot formed in one side wall thereof defining interior right angle walls for receiving the end of a photograph when the cutter is being employed.

A further object of this invention is to provide a cutter of the above mentioned character in which the slot formed in the side wall is directly above the cutting element or blade so that an exact measurement may be made as to the location of the slot desired before disfiguring the album sheet or leaf.

A further object of this invention is to provide a cutting blade attached to a block for convenient manipulation by the user with the length of the blade being slightly greater than the width of the gage slot formed in the block.

Other objects and advantages of the invention will become apparent during the course of the following description, taken with the drawing, wherein,

Figure 1 is a perspective view of the device embodying this invention;

Figure 2 is a side elevational view of the device illustrating the gage slot and the location of the blade directly thereunder;

Figure 3 is a vertical cross-sectional view of the cutting device illustrating the contour of the blade and its relationship with respect to the gage slot;

Figure 4 illustrates a bottom plan view of a cutter having a straight cutting blade and illustrating the manner in which it is located to extend the width of the gage slot;

Figure 5 is a bottom plan view of a modified form of the invention in which the cutting element is slightly curved and extends from the area adjacent the external right angle wall;

Figure 6 is a bottom plan view of a still further modified form of the invention in which the cutting element is shaped in a zig-zag fashion;

Figure 7 is a plan view of an album leaf illustrating the manner in which the cutting device is

to be employed when inserting photographs in the leaves of the album; and

Figure 8 illustrates a double leaf album sheet arranged to accommodate photographs on both sides thereof.

In the drawing, wherein for the purpose of illustrating the invention and wherein like reference characters will be employed to designate like parts throughout the same, the reference character 10 will generally be employed to designate a block of wood or other suitable material on the top of which is formed a knob 11 serving as a handle.

The underside of the block 10 is provided with a vertical slot 12 extending partly across the bottom surface adjacent one of the marginal edges thereof. Mounted within the slot 12 is a cutting blade 13 held in place by pins 14 and the cutting portion of the blade 13 extends beyond the bottom surface of the block 10 a distance slightly greater than the width of a sheet of card paper or cardboard from which the album leaves of albums are made.

Directly above the cutter blade 13 there is formed in one side wall of the block 10 a slot 15 having right angle walls 15a adapted to engage the edges of one of the corners of a sheet of paper or photograph.

As shown in Figs. 5 and 6 in the modified forms of the invention, the cutter blade 13a in Fig. 5 is arcuately curved and the ends of the cutter extend to the area adjacent the right angle walls 15b of the slot 15c.

In the modified form of invention as shown in Fig. 5, the cutter blade 13b is angularly bent at intervals to form a zig-zag slot in the album leaf which it has been found provides a neater appearance for the mounting of photographs which cover nearly the entire positive sheet.

The block as shown in Fig. 6 at 10b is identical to the form of invention shown in Figs. 1 to 5 inclusive and the slot 16b has its internal wall at right angles similar to the right angle walls 15a and 15b as shown in Figs. 4 and 5.

In Figs. 7 and 8, there is shown an album leaf 17 formed by a pair of sheets 18 and 19 fastened together along their outer free edges by means of a piece of adhesive 20 and fastened on their inner ends as at 21 in any suitable manner. Openings 22 may be formed in the album sheet 17 for insertion in the usual album. In Figs. 7 and 8, the mode of operating the cutter 10 is shown in dotted lines, it being understood that the cuts in the sheets 18 and 19 are made before the sheets are joined together at 20. The photo- 55

graph 23 has one of its corners inserted in the block 10 within the slot 15. After the corner of the photograph is positioned within the slot 15, pressure is applied upon the block 10 to cause the 5 blade 13 to cut a slot in the album sheet in the desired location so as to accommodate the corner of the photograph after the cutter block has been removed. By forming the leaves of the album 10 from a pair of sheets 18 and 19, photographs 23 may be mounted on both sides thereof and the corners of the photographs may be inserted in the slots 24. It is also to be understood that a blank sheet may be inserted between the joined 15 sheets 18 and 19 with the cuts later made, the blank sheet protecting the lower sheet of the joined pair from the cutter blade 13.

It is to be understood that various shapes of cutters may be employed in this device and that the form of the invention herewith shown and 20 described is to be taken as a preferred example or embodiment of the same.

I claim:

1. A cutting device of the character described, 25 comprising a rectangular block, a cutting blade mounted on the underside of the block adjacent one marginal edge thereof, a handle formed on the upper surface of the block and the side wall of the block having an opening therein adapted

to receive the corner of a photograph for gaging the location of the cutter.

2. A cutting device of the character described, comprising a rectangular block, said block having a V-shaped gage slot formed in one side wall 5 thereof, a curved cutter blade mounted on the bottom wall of the block, said cutter blade being within the projection of the V-shaped gage slot on the underside of the block and adjacent the side wall in which the opening of the slot terminates and a handle secured to the top wall of the rectangular block for manipulating the same. 10

3. A cutting device of the character described, comprising a rectangular block having a V-shaped gage opening at one side wall thereof, a 15 cutter blade mounted in the bottom wall of the rectangular block having areas bent at right angles forming a zig-zag cutting edge, and a handle secured to the top wall of the cutter block for the purpose of manipulating the cutter. 20

4. In a cutting device of the character described, a body, a cutter depending from the body and a guide carried by the body above the cutter adapted to receive the corner of a photograph or the like for locating the cutter relative to the sheet to be cut and said guide presenting the corner of the photograph or the like in a plane parallel to the lower edge of the cutter. 25
